UNITED STATES PATENT OFFICE.

WINTHROP L. CARTER, OF NASHUA, NEW HAMPSHIRE, ASSIGNOR TO NASHUA
GUMMED & COATED PAPER COMPANY, OF NASHUA, NEW HAMPSHIRE, A CORPORA-
TION OF MASSACHUSETTS.

COATED PAPER EXHIBITING PRINTED MATTER.

Application filed January 11, 1926. Serial No. 80,674.

This invention relates to the production of 5
coated paper bearing visible ornamentation
or designs or words, and has particular ref-
erence, although not limited thereto, to
5 waxed paper of the kind employed for bread
wrappers.

When coated paper is employed for wrap-
ping irregular or somewhat soft articles such
as loaves of bread or cake, the operation of
10 wrapping and the subsequent handling
causes more or less wrinkling of the paper
which is visibly emphasized in the coating
and is unsightly. When the coating is of a
waxy nature, such as paraffine, wrinkles or
15 creases show whiter than the rest of the area
of the paper, this being due to the cracking
of the wax, converting its smooth continuity
into very small particles.

One of the objects of my invention is to
20 utilize this characteristic of the coating to
save the expense of the ink usually em-
ployed for printing the paper to ornament
or cause it to indicate its origin, and to save
the time required to effect such printing.
25 Heretofore it has been customary, when it
is desired to ornament the paper or identify
the goods enclosed in waxed paper wrappers
by symbols or designs, words or names, to
first print the paper while in the web, and
30 then coat the ink-printed paper with par-
affine.

I attain the above mentioned object by
first coating the paper and then impressing
the symbols or other visible matter directly
35 in the coating without employing printing
ink or other coloring matter. This, when
the coating is paraffine, results in all of the
lines which form the symbols, designs, words
or names, showing what may be properly de-
40 scribed as a frosty white because of the
crushing effect of the impressions.

Another object of my invention is to coun-
teract or camouflage the appearance of
45 cracks or creases which may appear as the
result of wrapping or handling. I attain
this object by forming or providing, in the
coating, such designs or symbols or words or
names as will have the same appearance (ex-
50 cept as to shape) as cracks or creases, there-
by rendering such cracks or creases less no-
ticeable.

With the above mentioned objects in view,
my invention consists in the sheet material,
and the method of producing the same, sub-

stantially as hereinafter described and 55
claimed.

The drawing illustrates a piece of waxed
paper bearing one suitable kind of design
produced in the manner described herein.

In carrying out my present invention as 60
illustrated by the accompanying samples, the
paper, after being coated by a machine such
as illustrated in Letters Patent No. 1,140,-
873, granted to me May 25, 1915, or by any
other suitable waxing machine, is subjected 65
to the pressing action of what may be re-
ferred to as printing plates or type although
no printer's ink or other coloring substance
is employed, which pressing action simply
crushes the coating. Said plates or type may 70
be a part of any preferred printing mecha-
nism. In other words, any printing press
may be employed, but with the ink-applying
parts thereof removed or rendered inactive.
The web of paper may pass directly from 75
such a machine as illustrated in the Letters
Patent above referred to, to such printing
press, or it may be acted upon later to effect
the marking of the coating. In any case, it
is preferable that the paper, during the ac- 80
tion of the pressing plates or type, shall be
supported by an unyielding surface. For
instance, if the pressing plates or types are
carried by a revolving roll or cylinder, the
opposing and web-supporting roll or cylin- 85
der may well be of uncovered steel. And
the adjustment of the couple, viz: the co-
operating rolls or cylinders, will be such that
the pressing plates or types will not affect
the paper but only the coating. Therefore 90
the paper itself is not weakened in any way
due to the impression of the design in the
coating.

An expeditious method of practicing the
invention is to lead the paper, in the form 95
of a web, from such a waxing machine as il-
lustrated in the Letters Patent hereinbefore
referred to, and cause it to continue to travel
directly between the printing couple of a
suitable rotary printing press which latter 100
has no operative ink-supplying parts. The
coating, of course, is hardened as it leaves
the waxing machine.

To obtain the best results, when the paper
is heavily coated with wax, the adjustment 105
of the printing couple is such as to effect
somewhat greater pressure than is employed
for ordinary printing of uncoated paper

with ink. This is for the purpose of converting the smooth surface of the wax into clearly visible frosty white lines wherever the design plates or types bear on and crush 5 said coating.

Inasmuch as the reason for effecting any kind of printing on coated paper is chiefly for the purpose of identifying its origin or the goods to be wrapped therein, whether the 10 printing is purely a matter of ornamental design or consists of words or names, it is to be understood that in practicing my invention the identifying characters may be purely ornamental or descriptive by means 15 of words or names or anything capable of being impressed in the coating by plates or types or any equivalent thereof.

Designs produced in the manner described differ materially from the effect of making 20 impressions on waxed paper by means of heated dies or other implements, because in heating at a sufficient temperature to affect the waxed coating, instead of leaving any broken portions of the wax to cause a frosty 25 appearance, it simply leaves an impression

having a shiny surface and rendering the paper as a whole more transparent than the areas surrounding the design or impression.

Having now described my invention, I claim:—

1. Paper having a coating of wax having crushed portions to provide identifying characters in said coating.

2. Bread wrapping material comprising paper having a coating of wax bearing 35 frosty white identifying characters consisting solely of crushed particles of wax.

3. The method of producing wrapping material, consisting in coating paper with wax and then crushing portions of the wax 40 coating to provide white visible characters.

4. The method of producing wrapping material, consisting in coating paper with wax and then subjecting the material to the action of design-forming devices contacting 45 with wax-crushing pressure against the coating.

In testimony whereof I have affixed my signature.

WINTHROP L. CARTER.
